F. ROMANOWSKI

VEHICLE SIGNAL

Filed April 15, 1925

INVENTOR.
FRANK ROMANOWSKI

BY
Thomas Donnelly
ATTORNEY.

UNITED STATES PATENT OFFICE.

FRANK ROMANOWSKI, OF DETROIT, MICHIGAN.

VEHICLE SIGNAL.

Application filed April 15, 1925. Serial No. 23,228.

To all whom it may concern:

Be it known that I, FRANK ROMANOWSKI, a former citizen of the Republic of Poland, who have declared my intention of becoming a citizen of the United States, and residing at Detroit, in the county of Wayne and State of Michigan, have invented a new and useful Improvement in a Vehicle Signal, of which the following is a specification.

10 My invention relates to a new and useful improvement in a vehicle signal and particularly the method of attaching the vehicle signal upon the neck of the vehicle radiator.

It is an object of the present invention to 15 provide an attachment for a vehicle signal adapted for being mounted on the neck of the radiator, in which an expandable and contractible binding ring is used for gripping the neck of the radiator, the structure 20 being so arranged as to permit a ready release of the vehicle signal which serves as a closure for the radiator neck so that it may be tilted to permit the filling of the radiator, this invention being an improvement over 25 my invention which is shown in my pending application filed November 24th, 1924 and given Serial No. 751,811.

It is the object of the present invention to provide an attaching means of this class in 30 which the material used in the attaching means is reduced to a minimum and the machining necessary on the device also reduced to a minimum.

It is another object of the invention to 35 provide an attaching means of this class which when once secured upon the radiator neck will be locked thereon so as to prevent its undue removal.

Other objects will appear hereinafter.

40 The invention consists in the combination and arrangement of parts hereinafter described and claimed.

The invention will be best understood from a reference to the accompanying drawings which form a part of this specification and in which,

Fig. 1 is a front elevational view of the invention showing parts in section.

Fig. 2 is a fragmentary sectional view 50 taken on substantially line 2—2 of Fig. 1.

Fig. 3 is a top plan view of the attaching means with parts removed.

As shown in the drawings the invention is adapted for attaching a vehicle signal housing 7 to the neck 8 of the radiator of the vehicle with which used. The housing 7 is

provided with bulbs 9, 10 and 11 which may be vari-colored for signaling purposes. The housing is also provided with an opening 12 having a closure 13 mounted therein in 60 which may be inserted a thermometer to indicate the temperature of the water in the radiator, the thermometer being projected through and secured to, in any suitable manner, a tube 14 which is mounted in the neck 65 15 of the housing 7. The neck 15 is provided with a base having an outwardly projecting flange 16 which is adapted to rest upon a metallic ring 17 having bosses 18 and 19 formed at diametrically opposite points 70 each being provided with a threaded opening. Screws 18' and 19' are adapted for threading into the openings formed in bosses 18 and 19, each of these screws carrying at its upper end a keeper 18'' and 19'', respectively, which is adapted for being swung into a certain position, so as to clamp the base of the neck 15 in close engagement with the ring 17. The openings into which the screws 19' and 18' are threaded are slightly 75 reduced at their bottom to receive the heads of screws 21 and 20 which are adapted for threading into openings formed in bosses 22 and 23 formed on the clamping ring 24. As shown in Fig. 1 and Fig. 2, the bore of the 80 ring 24 has inclined side walls. These inclined side walls are adapted for engaging the inclined side walls of a gripping ring 25 which is split, so as to permit the approach and withdrawal of the ends of the ring 85 relatively to each other. This ring 25 is normally of less diameter than the neck 8 of the radiator, so that, when the ring 25 is turned upwardly the ends of this split ring approach each other to grip 90 tightly the neck of the radiator. When the rings are positioned in embracing relation upon the neck, a threading of the screws 20 and 21 into the bosses 22 and 23 will serve to 95 draw the ring 24 into close approach to the ring 17. The ring 17 is provided with a recess 26 for engaging the upper edge 27 of the ring 25, the engaging surfaces of the recess 26, or the ring 24 being beveled. As the ring 24 approaches the ring 17, since the 100 ring 25 is limited in its movement on account of its engagement with the ring 17, an approach of the ends of the ring 25 will be brought about on account of the engagement of the beveled engaging surfaces so that the 105 ring 25 securely clamps the neck 8 of the radiator. In this way a secure clamping of

110

the housing upon the neck of the radiator is provided having a minimum amount of material which considerably lessens the weight of the attaching means. Projecting from 5 the under surface of the neck 15 is a boss 36 in which is fixedly mounted a stirrup 29 having the ends 30 and 31 of its legs upwardly turned. Projecting inwardly of the inner surface of the radiator neck 8 on the ring 17 10 is a flange 32 which rests upon the upper edge of the neck 8 and serves to engage the turned ends 30 and 31 of the legs of the stirrup 29 when the locking fingers 18" and 19" are swung to inoperative position and 15 the vehicle signal housing section 7 raised to be tilted for permitting the filling of the radiator. In this way the housing 7 is prevented from being detached from the attaching means on account of the engagement 20 of the flange 32 with the angularly turned portions 31 and 30.

It is also apparent that the screws 18' and 19' will serve to lock the screws 20 and 21 in position so that they may not become 25 loosened, the screws 18' and 19' projecting downwardly into close proximity with the rings of the screws 20 and 21.

If desired the locking fingers 18" and 19" may be provided on their engaging ends 30 with grooves adapted to receive slight ribs or projections formed on the base of the neck 15.

While I have illustrated and described the preferred form of structure, I do not 35 wish to limit myself to the precise form of structure shown, but desire to avail myself of such variations and modifications as come within the scope of the appended claims.

Having thus described my invention, what I claim as new and desire to secure by Letters Patent is:

1. A securing means of the class described, comprising a split ring, adapted for mounting on a tubular supporting member in embracing relation, the peripheral surface of said ring being beveled toward one edge throughout a major portion of its surface and being oppositely beveled toward the opposite edge throughout the remainder of its surface; a locking ring adapted for mounting on said split ring having its inner surface beveled to engage the larger beveled peripheral surface of said split ring; bosses 45 projecting outwardly at diametrically opposite points on said locking ring; a co-operating ring adapted for resting upon the upper edge of said tubular member; and means for moving said locking ring into 50 close relation to said co-operating ring for clamping said split ring in clamping relation on said tubular member.

2. A securing means of the class described, comprising a split ring adapted for mounting 55 upon a tubular member in embracing

relation; a locking ring embracing said split ring for clamping said split ring into close engagement with said tubular member upon the moving of said locking ring relatively to said split ring in one direction; means 70 for moving said locking ring in said direction; a collar for receiving said moving means, said collar having a recess formed on its undersurface for engaging said split ring. 75

3. A securing device of the class described, comprising a split ring, adapted for mounting upon a tubular member in embracing relation; a locking ring adapted for mounting on said split ring in embracing relation and for moving said split ring into closely clamping engagement with said tubular member upon movement of said locking ring in one direction relatively to said split ring; a collar adapted for engaging the end surface 85 of said tubular member; screws projected through said collar and said locking ring for moving said locking ring in one direction for effecting a clamping of said split ring upon said tubular member; a housing mounted on said collar and swingable relatively thereto; an inwardly projecting flange on said collar; a yoke carried by said housing and having the extremities of its legs outwardly turned for engaging said inwardly projecting flange for permitting the tilting of said housing relatively to said collar and for preventing the removal of said housing from said collar. 90

4. A securing means of the class described, comprising a split ring, adapted for mounting in embracing relation upon a tubular member, the peripheral surface of said ring being beveled toward one edge through the major portion of its width and toward the other edge throughout the remainder of its surface; a locking ring adapted for mounting on said split ring in embracing relation, said locking ring having its inner surface inclined and adapted upon movement in one direction, for wedging said split ring into close engagement with said tubular member; a collar adapted for engaging the end surface of said tubular member and having a recess formed in its undersurface for engaging the peripheral surface of said split ring at one side thereof; a pair of bosses mounted on said locking ring having interiorly threaded sockets; a pair of bosses mounted on said collar in alignment with said bosses on said locking ring, adapted for permitting the threading of screws into said interiorly threaded sockets for effecting the approach of said locking ring to said collar, said bosses on said collar each provided with a socket enlarged throughout the major portion of its length and interiorly threaded; a housing mounted on said collar and having a base projecting radially outwardly of said collar toward its circumference; a 100

110

115

120

125

130

boss projecting downwardly from said housing interiorly of said collar; a yoke mounted on said boss projecting from said base and having the extremities of its legs outwardly turned; a flange projecting inwardly of said collar and adapted for engaging the outwardly turned ends of said legs upon a tilting of said housing relatively to said

collar; and means threaded into said enlarged sockets for retaining said housing in 10 non-tilting relation to said collar.

In testimony whereof, I have signed the foregoing specification at Detroit, in the county of Wayne and State of Michigan.

FRANK ROMANOWSKI.
